(57) **CLAIM**

The ornamental design for a gun sight as shown and described.

DESCRIPTION

Reproduction **1.1** is a front view of a first embodiment of a gun sight, showing our new design; reproduction **1.2** is a back view thereof; reproduction **1.3** is a left view thereof; reproduction **1.4** is a right view thereof; reproduction **1.5** is a top view thereof; reproduction **1.6** is a bottom view thereof; reproduction **1.7** is a perspective view thereof; reproduction **1.8** is another perspective view showing a variation state thereof.

Reproduction **2.1** is a front view of a second embodiment of a gun sight, showing our new design; reproduction **2.2** is a back view thereof; reproduction **2.3** is a left view thereof; reproduction **2.4** is a right view thereof; reproduction **2.5** is a top view thereof; reproduction **2.6** is a bottom view thereof; and reproduction **2.7** is a perspective view thereof.

The dash-dash broken lines in the reproductions depict portions of the gun sight that form no part of the claimed

(Continued)

design, and the dot-dash broken lines in reproductions 1.3 and 2.3 depict boundary lines of the claim that form no part thereof.
